UNITED STATES PATENT OFFICE

108,340

DESIGN FOR A SHOE

Frank Molea, New York, N. Y.

Application October 11, 1937, Serial No. 72,115

Term of patent 3½ years

To all whom it may concern:

Be it known that I, Frank Molea, a citizen of the United States and a resident of New York city, in the county of Kings and State of New York, have invented a new, original, and ornamental Design for a Shoe, of which the following is a specification, reference being had to the accompanying drawing forming part thereof, in which,

Fig. 1 is a plan view of the shoe showing my new design, and

Fig. 2 a side view of the shoe shown in Fig. 1.

A dominant feature of the design is seen in the two broad criss-cross strips of elastic material, such as lastex, connected at their rear ends with a heel portion of the upper, formed of other material such as leather, and combined with other material to form the vamp.

I claim:

The ornamental design for a shoe, as shown and described.

FRANK MOLEA.
